HANS HOLZWARTH, OF DUSSELDORF, GERMANY, ASSIGNEE TO HOLZWARTH GAS TURBINE CO., OF SAN FRANCISCO, CALIFORNIA, A CORPORATION OF DELAWARE

NOZZLE CHANNEL CONSTRUCTION FOR EXPLOSION TURBINES

Application filed February 25, 1929, Serial No. 342,639, and in Germany March 13, 1928. Renewed October 1, 1932.

My invention relates to explosion turbines and more particularly to the construction of the nozzle channel located between the outlet end of a combustion chamber of such turbine and its associated nozzle.

In the operation of explosion turbines, successive charges of air and fuel are exploded in the combustion chamber or chambers associated with the rotor of such turbine, and upon opening of the discharge or nozzle valve at predetermined instants the combustion gases are permitted to escape from the combustion chamber into a nozzle channel which directs them to a nozzle located adjacent to the blades of the rotor. The combustion gases are at a very high temperature and pressure as they enter the nozzle channel so that this element is constantly exposed to severe heat and pressure stresses.

It has hitherto been the practice to cast all of the nozzle channels for all of the combustion chambers integral with each other and with the machine frame. Such procedure had the disadvantage that if one of the nozzle channels was imperfectly cast the whole casting had to be discarded; also if one of the castings had some latent defect therein which was not obvious upon inspection, the same was very liable to crack under the severe stresses to which it was exposed during the operation of the turbine, in which event the whole machine had to be dismantled and the whole casting, which may have as many as ten nozzle channels formed therein, removed. Furthermore, when it has been the endeavor to make these nozzle channels as small as possible to avoid too large a loss of heat therein, the difficulty in casting was increased because the cores necessarily had to be small and as a result were easily displaced from their proper positions by the stream of molten metal during the casting operation. This was a serious disadvantage as each nozzle had to be correctly dimensioned both as to volume and surface area and in its position relative to the other channels.

It is an object of the present invention to overcome the above-mentioned disadvantages and I accomplish the same by so constructing the nozzle channels or individual channel

inserts that the rigidity of the former constructions is not sacrificed, but the necessity of accurate casting of the portion remaining integral with the frame is avoided. To this end I cast the machine frame in the known manner but provide enlarged openings or bores therein adapted to receive individual channel inserts which are fixed to the machine frame in the manner described hereinbelow. As a result, an apparent or latent defect in one of such channel inserts has no effect upon the remaining inserts and the same can be more easily and more economically replaced. The inserts are provided with cooling jackets to which a cooling medium may be charged to prevent overheating of the face of such channel inserts which is in direct contact with the hot combustion gases. I also so position these inserts within their respective bores that air jackets or pockets are formed between the inserts and the opposing walls of the machine frame and in this manner protect the main frame casting from the heat and pressure of the combustion gases.

The nozzle inserts are so constructed as to provide seats at their upper ends for the discharge or nozzle valve for the associated combustion chamber and are fixed at such end to the machine frame. The jacketed walls of the inserts may be made either rigid or flexible. In the first case the other ends of the channels are cast to project into annular grooves in the nozzle ring which are provided with yielding gaskets in such manner as to permit expansion of the nozzle channels at the high temperatures prevailing therein. Where, however, such inserts are provided with flexible walls they may be rigidly connected to the nozzle ring, the flexible walls taking up the expansion resulting from the heating thereof. I preferably provide also means in the form of flanged rings which are fixed upon the outlet ends of the channel inserts and serve to close the air jackets or pockets to insure against the flow of gas currents therein.

In the accompanying drawings are shown two embodiments of the inventive idea, but the same are to be understood as being shown by way of example only and not by way of limitation. In said drawings Fig. 1 is a

radial section taken through a nozzle channel and showing the outlet end of a combustion chamber and a nozzle channel insert associated with such chamber, the insert being formed of rigid walls; Fig. 2 is a similar view of another form of my invention in which the channel insert is formed of thin flexible walls; Fig. 3 is a partial section through a turbine plant embodying my invention; Fig. 4 is a section along the line 4—4 of Fig. 2; and Fig. 5 is a section along the line 5—5 of Fig. 3.

Fig. 1 shows the outlet end of a combustion chamber *a* from which the combustion gases are discharged upon opening of a nozzle valve *b* movable in a housing *c* located in the water or oil cooled machine frame or housing *d*, the gases escaping into a nozzle channel in nozzle insert *e* by which they are directed into a nozzle *f* arranged adjacent to blades *g* of the rotor *h*. The nozzle valve *b*, as well as the inlet valves of the explosion chamber *a*, is operated at the proper instants by any known mechanism, as by a hydraulic distributor of the type shown in the patent to Holzwarth No. 877,194.

In accordance with the present invention the nozzle channel *e* is not cast integral with the machine frame or housing *d* but is formed of a separate element or insert which is positioned within an enlarged bore within such frame. The inserts are provided at their upper ends with an annular flange which serves as a seat for the nozzle valve *b* and is fixed by means of screws *i* passing through such flange to the machine frame, suitable packing being preferably also provided to insure a gas-tight connection therebetween. The other or outlet ends of the inserts are provided with annular ribs or projections *e'* which are adapted to fit slidably into annular grooves *f'* in the nozzle ring *f''*, yielding gaskets or packings *k* being positioned between the opposing faces of the groove *f'* and the rib *e'*. The nozzle ring is fixed to the machine frame by means of screws *l*. The nozzle insert *e* is double walled to provide a cooling jacket or chamber adapted to receive a cooling medium such as steam, oil or water, which is charged thereinto by means of a conduit *m* and withdrawn therefrom through a conduit *n*. The channel insert is preferably provided with a rib *e''* which is so positioned with respect to the conduits *m* and *n* as to force the cooling medium to traverse the whole surface of the inner wall thereof and thereby prevent the formation of stagnant pools or pockets in the cooling chamber. The bore *d* in the machine frame, designed to receive the channel insert, is made of larger internal diameter than the external diameter of the insert both to facilitate insertion of the latter into such bore and also to provide an insulating air jacket *d''* between such channel

insert and the adjacent walls of the machine frame.

During the operation of the turbine the hot gases travelling through the channel *e* heat the latter and cause expansion thereof. This expansion is taken up by the sliding connection between the outlet end of the channel insert and the nozzle ring so that no undue stresses are set up in the several elements as a result thereof.

In the embodiment illustrated in Fig. 2 the upper or nozzle valve end of the insert *e* is shown attached to the machine frame in a manner similar to that shown in Fig. 1, a packing *o* being preferably provided between the flange on the insert and the wall of the machine frame contacting therewith. The insert is made double walled as is the corresponding insert in Fig. 1, except that the walls are made very thin and of flexible material, so that they can bend slightly to take up the expansion resulting from heating. The outlet or discharge end of the channel inserts in this embodiment of the invention is threaded to receive a correspondingly threaded flanged ring *p* which is rigidly connected to the nozzle ring *f''* and to the machine frame *d* by means of the screws *l*. The end face of the channel and the ring *p* and the opposing face of the nozzle ring *f''* are provided with grooves for receiving a gasket or packing *q'*. The advantage of employing a separate ring such as *p* is that the assembled ring and insert are more easily machined, so as to make a close fit with the machined rear face of the nozzle ring *f''*, than is the face of the machine frame *d* contacting the nozzle ring in Fig. 1. During the operation of the machine the expansion of the nozzle channel insert, whose ends are rigidly connected to the machine frame, is taken up by the flexible walls thereof and dangerous stresses therein thereby avoided.

It will be noted that in both Figs. 1 and 2 the walls, and particularly the gas-swept walls, of the insert *e* are considerably thinner than the walls of the machine frame, the walls of the insert in Fig. 2 being even thinner than those of the insert in Fig. 1 for the reasons given above. This construction reduces very greatly the stresses arising in the body of the insert due to the difference in temperature between the inner and outer faces of the gas-swept walls thereof, so that such insert is not subjected to excessive thermal stresses. The channel insert walls can safely be made quite thin compared with the walls of the frame, as such insert walls are not subjected to the weight, shock, vibration, and other stresses which the frame must withstand. The insert thus effectively protects the necessarily thick walls of the turbine frame against the hot combustion gases, which walls, in the absence of the insert, would suffer so large a temperature differen-

tial between the gas-swept and water-cooled faces thereof as to be in constant danger of rupture.

The mechanism shown in Figs. 2 and 4 may be assembled as follows: The member *e* is first inserted into the machine frame *d* and made to rest with its flange upon the support provided therefor, as shown at *o*, and is then fixed to such support by screws *i*. The ring *p* is then screwed into the threaded outlet end of the insert *e*. The surface *q'*, which comprises the outer surfaces of the ring *p* and the end of the insert *e*, is then planed until it is parallel with the surface of the housing *d* against which the ring *p* engages. Holes for the screws *l* are then drilled and tapped, and the nozzle put into place and clamped by means of the screws *l*.

Fig. 3 shows a general view of the turbine plant, the combustion chambers *a* being shown supported at their ends by the annular frame castings *d* and *r*. Fig. 5 is a view of the casting *d* and illustrates the size and complexity of the same. With very large turbines it is generally desirable to make this casting of two semi-annular sections which are bolted or otherwise connected to each other. Fig. 4 shows more clearly the construction of the expansion nozzle *f* which directs the explosion gases against the rotor blades.

Variations may be resorted to within the scope of the appended claims without departing from the spirit of the invention.

I claim:

1. In an explosion turbine, in combination, a frame, a combustion chamber supported by said frame and mechanism for periodically charging said combustion chamber with an explosive mixture to be exploded therein, a nozzle valve adapted to be opened at predetermined instants to permit discharge of the combustion gases from the combustion chamber, a rotor, a nozzle supported by and within said frame and arranged to discharge the combustion gases against said rotor, a connecting channel member insert disposed between the outlet end of said combustion chamber and said nozzle to conduct the hot, rapidly flowing gases to the latter, and positioned within said frame and separate therefrom so as to protect the same against the direct heat of the gases, said channel member insert consisting of two walls enclosing a cooling chamber and being fixed at its inlet end to said frame, a conduit for conducting a cooling medium to, and a conduit for withdrawing the same from said cooling chamber, whereby the inner gas-swept wall of said channel member insert may be made relatively thin so that during the operation of the turbine such a small temperature differential exists between the inner and outer surfaces of such wall that no excessive stresses arise therein.

2. The combination as set forth in claim 1, wherein the channel member insert is constructed at its inner end to provide a seat for the nozzle valve of the combustion chamber.

3. The combination as set forth in claim 1, wherein the outer end of the channel member insert is attached to the frame of the turbine, the walls of the insert being sufficiently thin to be capable of flexing to take up thermal expansion.

4. The combination as set forth in claim 1, wherein the channel member insert is spaced from the adjacent walls of the machine frame, whereby an insulating air jacket is formed therebetween.

HANS HOLZWARTH.
